(Cl. D58—13)

To all whom it may concern:

Be it known that I, Ernest R. Erickson, a citizen of the United States, and a resident of Des Moines, in the county of Polk and State of Iowa, have invented a certain new, original, and ornamental Design for a Bottom Member for Milk Bottle Carrying Cases and the like, of which the following is a specification, reference being had to the accompanying drawing, forming part thereof:

Figure 1 is a perspective view of a bottom member for milk bottle carrying cases and the like showing my new design.

Figure 2 is a top plan view thereof, and

Figure 3 is a side elevational view thereof.

I claim:

The ornamental design for a bottom member for milk bottle carrying cases and the like, substantially as shown.

ERNEST R. ERICKSON.
